UNITED STATES PATENT OFFICE.

ANDREW VON WEISENFLUE, OF SCRANTON, PENNSYLVANIA.

FILTER.

SPECIFICATION forming part of Letters Patent No. 310,157, dated December 30, 1884.

Application filed July 21, 1884. (No model.)

To all whom it may concern:

Be it known that I, ANDREW VON WEISEN-
FLUE, of Scranton, in the county of Lacka-
wanna and State of Pennsylvania, have in-
5 vented certain new and useful Improvements
in Strainers for Air-Pumps; and I do hereby
declare the following to be a full, clear, and
exact description of the same, reference being
had to the accompanying drawing, forming
10 a part of this specification, and to the figures
and letters of reference marked thereon.

In air-brake systems the valves of the air-
pump are oftentimes clogged and cut by rea-
son of the dust, cinders, &c., drawn in by the
15 operation of the pump through the suction-
pipe; and to remedy this it has been hereto-
fore proposed to place a piece of wire-gauze
over the nozzle of the suction-pipe; but the
fine dust will pass through the gauze and enter
20 the cylinder and cut the valves, as stated.
My invention therefore has for its object to
provide a filter for the air that will effectually
remedy the evils above referred to, and one
in which the filtering material can be readily
25 removed and cleansed or replaced; and it con-
sists in certain novelties of construction, which
I will now proceed to describe.

The drawing represents a sectional view of
an air-filter constructed in accordance with
30 my invention.

A represents the suction-pipe of the air-
pump, and to this pipe is secured the sectional
filter A'. The section B, secured to the pipe
A, is made conical, as shown, and is provided
35 near its outer or larger end with an internal
rib, b, to retain in place the piece of wire-net-
ting D. Hinged to the outer end of this sec-
tion B by means of hinge c is a correspond-
ingly-shaped portion, C, and near the larger
40 end of this section is secured a piece of wire-
gauze, E, as shown. The opening in the outer
end of the section C is relatively smaller than
the remainder of the attachment, whereby

the area of the filter is increased. The space
between the netting D and gauze E is filled 45
with either sponge or wool, or sponge and
horsehair, or any other suitable substance, to
arrest the passage of the dust through the
filter. From this construction it will be seen
50 that all air drawn in through the pipe A will
have to pass through the filtering material
and the dust will be arrested thereby, and
whenever it is necessary or desirable the filter-
ing material can be removed and cleaned or
55 renewed by swinging the sections apart, they
being normally held together by the spring-
catch b².

Although I have described my invention as
applied to the air-pump of an air-brake sys-
tem for railway-cars, it is evident that it can 60
be applied to any apparatus in which quanti-
ties of air are drawn in.

Having thus described my invention, I
claim as new—

1. In an air-filter, the combination, with 65
the two sections, hinged together as shown, of
a suitable filtering material placed within said
sections, and adapted to be removed or in-
serted by swinging the two sections apart, sub-
stantially as described. 7c

2. In an air-filter, the combination, with
two sections hinged together, and each pro-
vided with suitable netting or wire-gauze, of
a filtering material, such as described, placed
75 between them, and a catch or lock for holding
the sections together.

3. In an air-filter, the combination, with
two sections hinged together, of the filtering
material and the netting or gauze for hold-
ing the latter in place, substantially as de- 80
scribed.

ANDREW VON WEISENFLUE.
